CLAIM

We claim the ornamental design for the security tag holder,
as shown and described.

DESCRIPTION

FIG. 1 is a perspective illustration of a first embodiment of
a security tag holder;

FIG. 2 is a rear perspective illustration of the security tag
holder of FIG. 1;

FIG. 3 is a front view of the security tag holder of FIG. 1;
FIG. 4 is a rear view of the security tag holder of FIG. 1;
FIG. 5 is a first side view of the security tag holder of FIG.
1;

FIG. 6 is a second side view, opposite the first side view, of
the security tag holder of FIG. 1;

FIG. 7 is a top view of the security tag holder of FIG. 1;
FIG. 8 is a bottom view of the security tag holder of FIG. 1;
FIG. 9 is a perspective illustration of a second embodiment
of a security tag holder;

FIG. 10 is a rear perspective illustration of the security tag
holder of FIG. 9;

FIG. 11 is a front view of the security tag holder of FIG. 9;
FIG. 12 is a rear view of the security tag holder of FIG. 9;
FIG. 13 is a first side view of the security tag holder of FIG.
9;

FIG. 14 is a second side view, opposite the first side view,
of the security tag holder of FIG. 9;

FIG. 15 is a top view of the security tag holder of FIG. 9;
and,

FIG. 16 is a bottom view of the security tag holder of FIG.
9.

The broken lines form no part of the claimed design.

1 Claim, 12 Drawing Sheets
